UNITED STATES PATENT OFFICE

WILLIAM R. JEAVONS, OF CLEVELAND HEIGHTS, OHIO

REFRIGERATOR

Application filed November 8, 1930. Serial No. 494,343.

This invention relates to a refrigerator of the type wherein a refrigerant container is located within a food space which is enclosed by walls lagged against the transfer of heat. 5 This food space is cooled by the evaporation of a liquid in the container, which liquid evaporates at a temperature below the freezing point. The refrigerant container is usually located in the upper part of the food 10 space, and the refrigerator is provided with a door by means of which access to the food space may be obtained.

In the operation of refrigerators of this type, the quantity of fluid in the refrigerant 15 container varies in accordance with the cycle of operation of the particular device; at one time the container may be nearly full, while at another time it may be only partially full, or nearly empty. However, at practically all 20 times the upper portion of the refrigerant container is out of contact with the liquid therein. Even where the refrigerant container consists of an evaporating chamber encased within a brine-containing tank, the top 25 of such brine tank is nearly always out of contact with the brine contained therein. Hence, there is nearly always some portion of the metal casing for the refrigerant which is not in contact with the cooling liquid there- 30 in. When a refrigerator of the type referred to is in a quiescent condition, all portions of the exterior walls of the refrigerant container will attain a temperature below the freezing point, with the result that all such 35 parts will be entirely covered with hoar frost. However, when the refrigerator is in use, its door will be frequently opened for access to the articles contained therein as well as for the introduction of warm foods thereinto, 40 which results in a rise in temperature of the air within the refrigerator surrounding the container. A direct result of this interruption of the quiescent condition will be a rise in temperature above the freezing point of 45 the upper portions of the walls of the container, which are not in contact with the refrigerant, resulting in the surface melting of the body of hoar frost thereon, which frost is a poor conductor of heat. The water due 50 to the melting of the hoar frost on the upper

part of the refrigerant container will run downwardly and congeal into ice on the sides of the container which are at or below the freezing temperature. This water will melt only the surface of the hoar frost on such parts of the container as are maintained continuously at a temperature below freezing, and the water will soak into the porous, powdery hoar frost thereunder and into closer proximity to, or contact with, the freezing 55 surfaces of such parts. The repetition of this action over a period of several days will result in an accumulation of nearly solid ice on the portions of the container which may be maintained below the freezing point by contact of the refrigerant therewith, and this 60 accumulation becomes thicker from day to day.

It is usual to provide refrigerant containers with a tunnel-like freezing chamber projecting thereinto from the front or door-facing end of the container and so located with reference to the container as to be at all times surrounded by the refrigerant in the container and hence maintained constantly 65 at a temperature below the freezing point. This chamber is used for the reception of trays for ice cubes or receptacles for food to be frozen. It has been found that the mouth 70 of this freezing chamber, being a simple opening in the front of the container, is, because of the location of the chamber, at all times also subjected to a temperature below the freezing point. Hence, the water due to the melting of the frost on the parts of the 75 container above such mouth runs down the front wall of the container and freezes around the mouth and within the front of the same so that in a short time the mouth to the freezing chamber becomes obstructed and 80 clogged with ice so that a tray, food receptacle, or article in such chamber can be removed only with difficulty; in fact, it is frequently necessary to chop away the accumulated ice before the contents of the chamber 85 can be removed. It is, therefore, necessary, in order to permit convenient access to the freezing chamber, to stop the operation of the refrigerator periodically for the purpose 90 of allowing the parts of the refrigerant con- 95

tainer to be warmed sufficiently to melt the ice that has accumulated about and within the mouth of the freezing chamber. This melting operation is referred to as "de-frost-
5 ing".

It is the general purpose and object of my invention to prevent the formation of ice about and within the mouth of the freezing chambers of refrigerant containers and
10 thereby to render unnecessary the de-frosting operations heretofore employed for the purpose of clearing the mouths of or entrances to such chambers; and, inasmuch as the accumulation of ice on the other parts of
15 the container does not materially detract from the efficient operation of an ordinary refrigerator of the type to which my invention relates, my invention obviates the necessity for the frequent defrosting of such containers as practiced heretofore.
20

In the drawings forming part hereof, Fig. 1 is a sectional view through a portion of a refrigerator showing the refrigerant container with its tunnel-like freezing chamber, the said container being provided with my invention; Fig. 2 a view similar to Fig. 1, showing a modified form of the invention appearing in Fig. 2; Fig. 3 a view similar to Fig. 1 of a further modified form of my invention; and Fig. 4 a detail in perspective of the refrigerant container shown in Fig. 3.

Describing first by reference characters the various parts in Fig. 1, 1 denotes generally the rear wall, 2 the top wall and 3 a portion of the front wall of a refrigerator, these walls being constructed in a manner well known in the art to minimize heat transfer. The front wall is provided with a door 4 providing access to the food space 5 within which there is located the metal refrigerant container 6. The container shown herein is of the simple form wherein no surrounding brine tank is employed, the evaporating liquid 7 extending preferably as high as or
45 above the top wall of the tunnel-like freezing chamber 8, which projects into the body of the container from the front wall 9 thereof. A tray 10 having compartments therein for freezing water into ice cubes is shown within
50 the tunnel-like freezing chamber, the tray being provided with a handle 11. In the form of my invention shown in Fig. 1, the mouth of the chamber 8 is extended forwardly or toward the door 4 by means of an
55 integral extension 12 and is provided at the front end of such extension with a facing flange 13 which extends at right angles thereto (parallel with the front of the container) and is shown as provided with a rearwardly deflected edge 14, the external dimensions of the flange being approximately the same as the front of the container 6, whereby the flange forms a spaced finishing face for the front of the container.
65

In order to understand the manner in

which the extension 12 prevents the formation of ice about the mouth of the freezing chamber, it should be explained that the cooling of the space 5 within the refrigerator is due entirely to the refrigerant container in the upper portion of such space and that air contacting with this container drifts downwardly and, absorbing warmth and moisture from the foods and other articles within the refrigerator, drifts upwardly to the top of the space, where it again contacts with the cold exterior of the container, with the result that the moisture therein is condensed on the exterior of such container. The extension 12 constitutes a shield which prevents the formation of ice in and about the mouth of the freezing chamber, this shield projecting above the entrance to or mouth of the freezing chamber to a point in the space where it will periodically attain a temperature above freezing. This periodical attainment of such temperature is caused by the opening and closing of the door 4 for the insertion of food into and the removal of food from the refrigerator, as well as by the influence of the relatively warm foods which are placed within the refrigerator; which cause a temporary warming of the air in the space 5. The shield prevents water that may run down the front of the container 6 from freezing on any permanently cold parts in or about the mouth of the freezing chamber, as, due to the extension of such mouth by the shield 12, there are no such permanently cold parts in or about such mouth. The shield operates to secure this result by protecting this extended mouth of the freezing chamber from access of moisture-laden air thereto from above. This action of the shield is indicated on Fig. 1, wherein 15 denotes ice that has been formed by the contact of the downwardly-flowing or drifting moisture-laden air with the front wall 6 of the said container and with the said shield. The shield projects forwardly a sufficient distance from the cold wall of the container so that any slight frost or ice accumulation that may occur at its front or outer end will be melted, at least periodically, to water which will drain to points such that, on re-freezing, it will cause no obstruction of the mouth of or entrance to the freezing chamber.
110

Where the front or outer end of the shield 12 is flanged, as shown in Fig. 1, it has been found that the length of the extension or shield need not be more than $\frac{3}{4}$ of an inch or one inch, as the flange (due to its area), and the extended mouth of the tunnel, will periodically attain a temperature above freezing and thus prevent such an accumulation of ice as will obstruct the mouth of or entrance to the freezing chamber and interfere with the removal of the contents thereof.
115

In Fig. 2 there is shown a modification of my invention wherein the freezing cham-
120
125
130

ber 8 is provided with an extension 16 constituting a shield and shown as an integral continuation of said chamber. In this case, the flange 13 is omitted and the shield is extended closer to the door 4. The shield in this case may be from $1\frac{1}{2}$ to 2 inches in length; but it will have the same effect in preventing obstruction of the mouth of or entrance to the chamber 8 as the shield shown in Fig. 1. Having its front or outer end in closer proximity to the door 4 is advantageous, as the inner surface of the door is nearly always at a temperature well above the freezing point, and the proximity of the outer front end of the shield to the door contributes to its efficiency not only because it insures proper temperature conditions for such end of the shield as will prevent any detrimental accumulation of ice thereon and therewithin, but the door also forms in effect a partial closure for the freezing chamber from the drift of the moisture-laden air from above and thus minimizes the opportunities for any detrimental accumulation of ice on or within the outer end of said shield. If the outer edge of the shield is in close proximity to the door, the door will function to prevent nearly all of the moisture-laden air from above from contacting with the interior of the outer end of the shield whether this outer end is or is not at the freezing temperature. The outer end of the shield in this case will be periodically (if not continuously) at a temperature above freezing whereby there can be no such accumulation of ice as will interfere with the removal of the tray 10 or any other articles which may be placed within the freezing chamber, and this despite the absence of the flange employed with the former shield.

In Figs. 3 and 4 there is shown a further modification of my invention wherein the shield-like extension 17 is open at the bottom. It has been found that a shield thus constructed will operate efficiently to prevent such obstruction of the mouth of or entrance to the freezing chamber as will prevent or interfere with the removal of the contents of such chamber. This will be readily understood from the fact that the moisture-laden air, as well as the water resulting from the melting of the frost on the upper part of the container 6, will flow downwardly, not only along the front face of the container but also in contact with the top and downwardly along the sides of the shield and that there will be no detrimental accumulation of ice within the lower edges of the sides of the shield as well as on the front or outer edge of the same.

Having thus described my invention, what I claim is:

1. The combination, with a refrigerator having a space for the reception of food and a door, of a refrigerant container within said

space and having a freezing chamber projecting thereinto from one of the walls thereof, and a shield for the mouth of said chamber, the said shield extending outwardly from said wall a distance sufficient to subject the outer end of said shield at least periodically to a temperature above the freezing point whereby the entrance to said chamber through said shield will not be detrimentally obstructed by an accumulation of ice.

2. The combination, with a refrigerator having a space for the reception of food and a door, of a refrigerant container within said space and having a freezing chamber projecting thereinto from the wall thereof which is presented toward said door, and a shield for the mouth of said chamber, the said shield constituting an extension of said chamber and projecting outwardly from said wall a distance to subject the outer end of said shield at least periodically to a temperature above the freezing point whereby the entrance to said chamber through said shield will not be detrimentally obstructed by an accumulation of ice.

3. The combination, with a refrigerator having a space for the reception of food and a door, of a refrigerant container within said space, the said container having a freezing chamber projecting thereinto from the wall thereof which is presented toward said door, the said chamber being located below the top of the said container, and a shielding extension of said freezing chamber projecting therefrom toward and in proximity to said door.

4. The combination, with a refrigerator having a space for the reception of food and a door, of a refrigerant container within said space and having a freezing chamber projecting thereinto from one of the walls thereof, and a shield for the mouth of said chamber, the said shield extending outwardly from said wall and being so positioned as to prevent water or moist air from above from contacting with and congealing upon the cold entrance walls of the freezing chamber.

5. The combination, with a refrigerator having a space for the reception of food and a door, of a refrigerant container within said space and having a freezing chamber projecting thereinto from one of the walls thereof, a shield for the upper portion of the mouth of or entrance to said chamber projecting outwardly from the said wall and constituting an outward extension of the upper portion of said chamber, the outer end of such shield projecting to a point where it is subjected at least periodically to a temperature above the freezing point whereby the outer end of the shield and the entrance to said chamber will not be materially obstructed by an accumulation of ice.

6. The combination, with a refrigerator having a space for the reception of food and

- a door, of a refrigerant container within said space and having a freezing chamber projecting thereinto from one of the walls thereof and below the top thereof, and a shield constituting an extension of the said chamber and projecting outwardly from said wall and being provided with a flange at its outer end.
7. The combination, with a refrigerator having a space for the reception of food and
- 10 a door, of a refrigerant container within said space and having a freezing chamber projecting thereinto from one of the walls thereof and below the top thereof, and a shield constituting an extension of the said chamber
- 15 and projecting outwardly from said wall and being provided with a flange at its outer end substantially parallel with the wall from which such shield extends, the outer flanged end of said shield extending to a point where
- 20 it is subjected at least periodically to a temperature above the freezing point whereby the outer end of said shield and the entrance to said chamber will not be materially obstructed by an accumulation of ice.
- 25 In testimony whereof, I hereunto affix my signature.

WILLIAM R. JEAVONS.
